UNITED STATES PATENT OFFICE.

DAVID GRAVEL, OF CHATTANOOGA, TENNESSEE.

APPARATUS FOR SINGEING YARN.

1,325,891.

Specification of Letters Patent. Patented Dec. 23, 1919.

Application filed August 23, 1918. Serial No. 251,095.

To all whom it may concern:

Be it known that I, DAVID GRAVEL, a citizen of the United States, residing at Chattanooga, Hamilton county, and State of Tennessee, have invented and discovered certain new and useful Improvements in Apparatus for Singeing Yarn, of which the following is a specification.

The present practice of preparing yarn for the majority of uses includes a singeing operation. This is at present accomplished by running the yarn from the spools on the creel through a warping machine and then balling the warp. The ball is then transferred to another frame and the yarn or warp passes through a tensioning device, then through an expansion comb mounted on a portable singeing machine. From this machine the yarn passes through a leese comb which is mounted on a stationary frame or support and is then rewound on a balling machine.

This system not only necessitates balling the warp twice, but also requires the constant attention of the operator as there is no automatic means for stopping the machine should the yarn become broken or tangled. When the yarn does break it is necessary for the operator to lower the singeing device, which at the same time brings the yarn to a standstill but not until from six to eight feet of the yarn has passed the singeing machine without being singed. After the broken yarn has been repaired, the singeing machine is moved forward on a pair of rails to a point in advance of the unsinged yarn and then raised into the singeing position again and slowly returned to its former position. The system just described does not satisfactorily singe the yarn, as only the underside thereof is presented to the flame.

My said invention relates to an improved method and means for accomplishing this work by which the difficulties of and objections to the system just described are obviated and the yarn is treated from both the lower and upper sides, all of which will be hereinafter described and claimed.

My system consists of running the yarn from the spools on the creel through a warping machine and over a series of flames or burners mounted in a stationary frame. From this frame the yarn passes around an idle roller which turns the yarn into the reverse position presenting its upper surface

to another series of burners. It is well understood that sufficient singeing is accomplished by about three burners, but I employ six or more divided into two groups 60 for a purpose to be explained later. After the yarn has passed over the first set of burners and the first idle roller, it is subjected to the action of a second set of burners before it is finally wound by the balling 65 machine.

Another feature of my invention resides in connecting the present automatic stop device of the warping machine with the burner shields and gas valves of my singeing machine.

In the accompanying drawings which are made a part hereof, like reference characters designate similar parts in the several views, of which

Fig. 1 is an elevation of a portion of the apparatus showing the creel, the warping and the balling machine,

Fig. 2, a continuation of Fig. 1, showing the singeing machine and the idle pulleys,

Fig. 3, an elevation of the singeing machine,

Fig. 4, a detail plan view as seen from dotted line 4—4 on Fig. 3,

Fig. 5, a detail cross section through the 85 burner and shield on the dotted line 5—5 in Fig. 4, and

Fig. 6, a detail view of the lever holding latch.

The apparatus consists of a creel A upon which is mounted a series of spools 10 carrying threads of yarn 11 which are led through an expansion comb 12 mounted on any suitable warping machine B. The yarn passes under and over a series of rollers and through the drop wires of the stop motion of the warping machine B in the form of a warp C which passes to the singeing machine D. This machine comprises a frame 13 having supports 14 and 15 formed integral with an upper horizontal member 16 and an intermediate member 17 which have mounted thereon bearing brackets 18 supporting perforated burner tubes 19. Valves 20 are secured to one end of the tubes 105 19 and are connected to a manifold 21 by pipes 22. Gas is conveyed to the manifold through a pipe 23 provided with a valve 24 for cutting off the supply of gas to the entire machine. The lower end of pipe 23 is 110 provided with an upstanding nozzle 25 which is mounted in the open end 26 of the

manifold in such a position that air is drawn in and mixed with the gas before it enters the tubes 22. The stems of each of the valves 20 are provided with a sprocket wheel 27 connected for simultaneous operation by sprocket chains 28, shown in Figs. 2 and 3. Connecting rods 29 have their upper ends joined to the chains 28 and their lower ends connected to a lever 30 fulcrumed at 31 to a bracket 32 secured to the support 14. This lever 30 extends twice as far on one side of its fulcrum 31 as it does on the other and the short end carries a link 33 which is connected to a lever 34 mounted on the stem of a quick-acting valve 35 in the gas pipe 23 which controls the flow of gas to the manifold 21. Each of the burners is provided with a pilot light 36 fed by the pipe 37 which is provided with a regulating valve 38 and which connects with the main gas pipe 23 at a point below the valve 24. The long end of the lever 30 has fulcrumed thereto a connecting link 39 upon which is secured a counter-balance of proper weight. The lower end of the link 39 connects with the long arm 40 of a lever 41 fulcrumed at 42 to a beam 43 which is secured at one end to the standard 15 and at the other end to a bracket depending from the frame of the working machine B.

The short arm 44 is designed to alternately contact with a pair of pivoted latches 45 and 46 when the machine is out of operation or in operation respectively. These latches 45 and 46 are pivoted on a T-shaped lever 47 fulcrumed to the beam 43 at 48 and are held in normal positions by a spring 49 secured to studs 50 on each latch member. A foot member 51 is fulcrumed on a shaft 52 mounted in the frame of the warping machine B and is connected to the lever 47 by means of the rod 53 to swing the lever from its upper to lower position, or vice versa. The lever 51 carries means to operate the device 54 for shifting the driving belt 55, which through a train of gears, operates to drive the balling machine E, shown only in Fig. 1. The lever 51 is also connected by means of a rod 64 with the stop motion of the warping machine.

As a matter of convenience to the operator, a foot lever 56 is mounted on a shaft 57 which runs across the entire machine and has formed integral therewith an upstanding arm 58 connected to one arm 59 of a bell-crank lever 60 by means of a connecting rod 61. The lever 60 is pivoted on a stub shaft 62 carried by a depending bracket secured beneath the beam 43. The other arm 63 of said lever 60 is connected also to the rod 53 so that the entire machine may be started by applying sufficient pressure to the lever 56.

Each burner is provided with a semi-cylindrical shield 64 of metal which is lined

with asbestos 65 and which is mounted between two castings 66 to which are secured two flat strips 67 and 68. The strip 67 serves to keep the shield in proper alignment and also serves to lift the warp away from the shield when in its upper position. The strip 68 is made longer than the shield and at one end is bolted to the sprocket 27 and the other end is bolted as at 69 to a cap 70 which closes the end of the tube 19. Counter weights 71 are secured to each of the sprockets 27 to overcome the weight of the shields 64. The usual expansion combs 72 and leese comb 73 are provided to keep the yarn separated. An idle drum 74 is also provided for carrying and returning the warp through the lower flame with a second idle drum 75 to again turn the warp to the eye 76 and over a third idle drum 77 turning the warp to the balling machine E.

The operation of the device is as follows:

The yarn passes from the creel, through the automatic stop motion of the warping machine and emerges therefrom as a warp. The warp then passes through the flames of the upper set of burners and around the idle drum, which turns the yarn, so as to present the unburned side to the lower set of burners, thereby completely singeing the nap from all sides of the yarn. The singed warp then passes around another idle drum and is then collected into the form of a band or rope by passing through an eye mounted on the same standard with another idle pulley from which it leads to the balling machine.

Should the yarn break in the warping machine, the automatic stop device would cause the lever 51 to raise, shifting the belt 55 so as to stop the balling machine and at the same time release the lever 44 from the latch 46 permitting the weight to rock the series of levers so as to shut off the valves 20 and 35 and raise the several shields 64. During this interval the warp has advanced about six feet which causes a corresponding length of warp to pass the upper set of burners without being singed. However when the yarn is repaired and the machine again started, by manually releasing the lever 44 from the latch 45 and depressing the said lever into locking engagement with the latch 46, the unsinged portion will be completely singed by passing through the flames of the lower set of burners.

Having thus fully described my said invention, what I claim as new and desire to secure by Letters Patent, is:

1. In an apparatus for singeing yarn the combination of means for causing the yarn to travel in super-posed series of parallel strands and in opposite directions, a plurality of burners located beneath the yarn strands of each series, a common intake manifold for said burners, said burners each

having a flame guard, gravity actuated means for said guards, a plurality of chains connected to operate the guards, and a common manually controlled lever connected to 5 actuate said guard chains, substantially as set forth.

2. In an apparatus for singeing yarn, the combination of means for causing the yarn to travel, a burner tube having a plurality 10 of flame jets, a control for said burner, a pivotally mounted guard for the burner tube, gravity actuated means for said guard, a chain and sprocket gearing connected to said guard, and a manually controlled lever 15 connected to actuate said chain and sprocket gearing, substantially as set forth.

3. In an apparatus for singeing yarn, a burner, a source of fuel supply for the burner, a rotatably mounted guard to cover 20 the burner, and connected means for simultaneously rotating the guard over the burner and interrupting the fuel supply.

4. An apparatus for singeing yarn comprising a burner, a source of fuel supply 25 for the burner, means to move the yarn to be singed in juxtaposition to the burner, a guard rotatably mounted to be interposed between the yarn and the burner, and means to simultaneously rotate the guard and interrupt the fuel supply.

5. In an apparatus for singeing yarn, a burner, a source of fuel supply for the burner, a valve for controlling the flow of fuel to the burner, means to pass the yarn 35 in juxtaposition to and be acted upon by the burner, a guard rotatably mounted adapted when rotated to be interposed between the yarn and the burner, and means to simultaneously rotate the guard and actuate the valve.

6. In an apparatus for singeing yarn a warping machine having means for interrupting the drive when the thread breaks, a burner, a source of fuel supply for the burner, means to conduct the yarn from the warping machine into juxtaposition to and be acted upon by the burner, a guard positioned in juxtaposition to the burner, and means actuated from the stopping mechanism of the warping machine to move the 45 guard rotatably between the yarn and the burner and simultaneously interrupt the fuel supply.

7. In an apparatus for singeing yarn, a warping machine, a burner, means to conduct the yarn from the warping machine and into juxtaposition to the burner, a source of fuel supply for the burner, a guard mounted to move rotatably between the 50 yarn and the burner, and means actuated from the warping machine stopping mechanism to simultaneously move the guard rotatably between the yarn and the burner and to interrupt the source of fuel supply.

8. In an apparatus for singeing yarn, a

plurality of burners each provided with a rotatably mounted guard, positioned when rotated to cover the flame emitted from the burner, and means connecting the several guards to rotate said several guards simultaneously. 70

9. In an apparatus for singeing yarn, a plurality of burners mounted in upper and lower tiers, a guard rotatably mounted in juxtaposition to each of said burners and 75 adapted to cover the flame emitted from the burner, and means adapted to simultaneously actuate the several guards.

10. In an apparatus for singeing yarn, a plurality of burners mounted in an upper 80 and lower tier, a guard provided for each of said burners and rotatably mounted to cover the flame emitted from the burner, means to pass the yarn successively above the burners of the upper and lower tiers, and means connecting and adapted to simultaneously actuate the several guards. 85

11. In an apparatus for singeing yarn, a plurality of burners mounted some above others, a guard for each of said burners rotatably mounted to cover the flame emitted from its respective burner, means to cover the flame emitted from its respective burner, means to pass the yarn successively into singeing juxtaposition to the burners of the 95 several tiers, and means connecting and adapted to simultaneously actuate the several guards.

12. In an apparatus for singeing yarn, the combination of a warping machine having a 100 stop mechanism, of a plurality of burners each provided with a rotatably mounted guard, a source of fuel supply common to the several burners and connected means for simultaneously rotating the several guards 105 into a position between the yarn and the burner and to interrupt the flow of fuel.

13. In an apparatus for singeing yarn, a plurality of burners having each a rotatably mounted guard, sprockets carried by the 110 guards, and a sprocket chain passing over the several sprockets and adapted to simultaneously rotate the several guards.

14. In an apparatus for singeing yarn, the combination of a plurality of burners 115 mounted in upper and lower tiers, a rotatably mounted guard for each of said burners, a sprocket carried by each of said guards, a sprocket chain passing over the several sprockets and a manual lever connected with and adapted to actuate the sprocket chain. 120

15. In an apparatus for singeing yarn, the combination of a warping machine having a stop mechanism of a plurality of burners 125 mounted in upper and lower tiers, means to conduct yarn from the warping machine successively into singeing juxtaposition to the burners of the several tiers, guards mounted to move rotatably between the yarn and the 130

burners, manual means for moving the guards out of interposition, and means actuated from the stop mechanism of the warping machine for releasing the guard operating mechanism and permitting said guards to return to their interposed position.

16. In an apparatus for singeing yarn, the combination with a warping machine of a plurality of burners mounted in upper and lower tiers, a source of fuel supply for the burners, means to conduct the yarn successively into singeing juxtaposition to the burners of the several tiers, a guard provided for each of said burners, a sprocket carried by each of said guards, a sprocket chain passing over the several sprockets, gravity means for actuating the sprocket chain to operate through the sprockets to

move the guards rotatably into position between the yarn and the burners, gravity means for moving the guards into such interposition, means to manually move the guards out of position against gravity, and to lock such guards in such inoperative position, and means actuated from the stop mechanism of the warping machine for releasing the gravity mechanism to return the guards to interposition.

In witness whereof I have hereunto set my hand and seal at Chattanooga, Tennessee, this 20th day of August, A. D. nineteen hundred and eighteen.

DAVID GRAVEL. [L. s.]
